UNITED STATES PATENT OFFICE.

JOSEPH F. HEWITT AND ROBERT HEWITT, OF ALLEGHENY, PENNSYLVANIA.

DESIGN FOR A FIREPLACE GAS-BURNER.

SPECIFICATION forming part of Design No. 27,355, dated July 13, 1897.

Application filed February 5, 1897. Serial No. 622,222. Term of patent 7 years.

To all whom it may concern:

Be it known that we, JOSEPH F. HEWITT and ROBERT HEWITT, citizens of the United States, residing at Allegheny, in the county 5 of Allegheny and State of Pennsylvania, have invented and produced a new and original Design for Fireplace Gas-Burners, of which the following is a specification.

In the accompanying drawings, which make 10 part of this specification, Figure 1 is a front elevation of our improved design for a fireplace gas-burner. Fig. 2 is a vertical section of the same, and Fig. 3 is a horizontal section thereof.

15 Our design relates to fireplace gas-burners, and more particularly to those which are used in grates.

In the several drawings which constitute 20 part of this specification, 2 2 are the usual filling-strips, and 3 the fender. These are merely shown for the purpose of illustration, and our design relates to what is commonly known as the "backboard" only. This back-

board 3 is in the form of a compound curve in horizontal sections, as clearly seen in Fig. 25 3. It may be provided with projecting ribs extending transversely across the face thereof, as seen at 4 4, or these ribs may be omitted. If desired, the backboard may be surrounded by a border giving a rope-like effect 30 at 5, but the fundamental feature of our design is the backboard having the wave-line effect in horizontal cross-sections. 6 6 are the usual gas-outlets.

Having described our invention, we claim— 35

The design for a fireplace gas-burner, substantially as herein described and shown.

In testimony whereof we have hereunto set our hands this 4th day of February, A. D. 1897.

JOSEPH F. HEWITT.
ROBERT HEWITT.
